UNITED STATES PATENT OFFICE.

THOMAS E. BARNUM, OF MILWAUKEE, WISCONSIN, ASSIGNOR TO THE CUT-
LER-HAMMER MFG. CO., OF MILWAUKEE, WISCONSIN, A CORPORATION
OF WISCONSIN.

THREE-WIRE REVERSIBLE-DRUM CONTROLLER.

No. 844,652.

Specification of Letters Patent.

Patented Feb. 19, 1907.

Application filed October 3, 1904. Serial No. 227,016.

To all whom it may concern:

Be it known that I, THOMAS E. BARNUM, a citizen of the United States, residing at Milwaukee, in the county of Milwaukee and State of Wisconsin, have invented new and useful Improvements in Three-Wire Reversible-Drum Controllers, of which the following is a full, clear, concise, and exact description, reference being had to the accompanying drawings, forming a part of this specification.

The present invention relates to improvements in electric-motor controllers, it being the object thereof to provide a controller which shall be capable of regulating an electric motor to obtain a wide variation in the speed thereof and also of controlling the direction of operation of the motor and which shall be efficient and compact.

The present invention, when embodied in the preferred form thereof, contains a rotatable member carrying contacts and adapted to be rotated in either direction from the initial position thereof, and another rotatable member, also carrying contacts and rotated always in the same direction from the initial position thereof by means operated by the former member.

An embodiment of the present invention, which will serve to explain the invention, has been illustrated in the accompanying drawings, in which the several figures are as follows:

Figure 1 is an elevation of the interior mechanism of a controller constructed in accordance with the present invention, the casing of the controller being in section. Fig. 2 is a cross-section through said controller on the line 2 2 of Fig. 1. Fig. 3 is a similar view on the line 3 3 of Fig. 1, and Fig. 4 is a diagram of the motor-circuits and the contacts of the controller developed in a plane.

In the controller illustrated in the drawings an operating-shaft 1 may be journaled within a suitable casing 2 and have the upper end thereof extended through the top of the casing and connected to a hand-wheel 3 or other device for turning the same. A latch 4, adapted to engage stops 5, may be carried by the hand-wheel to lock the same in the initial position thereof, and this latch may be actuated to release the hand-wheel by a button 6, which has a stem 7, extending

through the handle of the hand-wheel and engaging the latch.

The operating-shaft has mounted thereon shells 8 8^a, which are preferably supported by a bracket 9, fastened upon said shaft and which carry reversing switch-contacts 10. These shells are insulated from each other and are connected at the bottom by an insulating-plate 11. Also upon the operating-shaft are mounted disks 12, which carry contacts 13 of a main-line switch. The reversing switch-contacts and the main-line switch-contacts are adapted to engage contact-fingers or circuit-terminals 14 and 15, respectively, which are preferably mounted upon a block 16. These terminals are connected in circuit, as shall be hereinafter explained, and between the same are preferably placed insulating-partitions 17.

The main-line switch-contacts 13 and the terminals 15, adapted to be engaged thereby, are preferably protected from an arc forming between the same by a blow-out magnet 18, which may be mounted upon a plate 19. Also within the casing may be journaled a counter-shaft 20, upon which may be mounted a shell 21, supported by a bracket 22, fastened upon the counter-shaft. This shaft preferably has mounted thereon a contact 23, adapted to engage contact-fingers or circuit-terminals 24, and also contacts 25, adapted to engage contact-fingers or resistance-terminals 26. These contact-fingers or terminals are preferably mounted upon a block 27. Upon a stationary plate 28 are mounted a series of contacts or resistance-terminals 29, arranged in a plane substantially perpendicular to the axis of the counter-shaft. These resistance-terminals are adapted to be engaged by contacts or brushes 30, mounted upon a plate or block 31, supported by the shell 21.

The counter-shaft may be provided with a notched wheel 32, which is engaged by a lever 33, actuated by a spring 34. This wheel and lever regulate the operation of the controller, and said wheel may be provided with a notch for each division in the armature resistance. The counter-shaft has fastened thereto a pinion or gear 35, with which meshes a segmental gear 36, pivoted to the casing, and this segmental gear may be connected by a link 37 to an arm 38, fastened upon the

operating-shaft. When the operating-shaft is turned, the arm 38, acting through the link 37, moves the segmental gear 36. The pinion 35 being driven by the segmental gear, 5 the counter-shaft will be rotated simultaneously with the operating-shaft. In the initial position of the parts of the operating mechanism of the counter-shaft the point of connection of the link to the arm lies substantially in alignment with the axis of the operating-shaft and the point of connection of the link to the segmental gear. Consequently the operating-shaft may be turned in either direction from the initial position 15 thereof, and still the counter-shaft will always be rotated in the same direction from its initial position. The mechanism for driving the counter-shaft is preferably adapted to turn said shaft substantially a complete 20 revolution, while the operating-shaft turns substantially a half-revolution.

The operation of the controller shall be explained in connection with the diagram of circuits illustrated in Fig. 4. In this diagram the various contacts are shown developed in a plane. As there are often several contacts serving a similar purpose, the reference-numerals heretofore employed to indicate some of said contacts shall be supplemented by reference-letters in some instances to distinguish the contacts of the same kind. When the parts of the controller are in the initial position thereof, the contacts assume the relation indicated in the diagram. The 35 contact-fingers or resistance-terminals 26 may be connected by conductors to an armature resistance 39, and the contacts or resistance-terminals 29 may be connected by conductors to a field resistance 40. The motor 40 to be controlled may have an armature 41 and a field 42, and the current for operating this motor may be supplied from a multi-voltage system of electrical distribution, which may have conductors 43, 44, and 45, 45 the conductor 43 being positive, the conductor 44 neutral, and the conductor 45 negative. The voltage between the positive and neutral wires may be two hundred and twenty 50 volts, while the voltage between the positive and neutral conductors or the negative and neutral conductors may be one hundred and ten volts.

If the controller-handle be turned so that both members thereof will move in the direction indicated by the arrow, then the armature-circuit will first be closed from the conductor 43 through the contact-finger 15^b, motor switch-contacts 13^a 13^b, respectively, contact-finger 15^a, blow-out magnet 18, conductor 46; contact-finger 14^a, reversing switch-contacts 10^c 10^d, respectively, contact-finger 14^t, conductor 47, armature 41, conductor 48, contact-finger 14^e, conductor 49, contact-finger 14^b, reversing switch-contacts 10^b 10^a, contact-finger 14^a, conductor

50, contact-finger 26^t, conductor 51^c, contact-finger 26^e, all the armature resistance 39, contact-finger 26^a, contact 25^a, contact 23, and contact-finger 24^a, to the negative conductor 44, and the field-circuit will exist from the 70 positive conductor 43 through field 42, conductor 52, contact 29^a, brushes 30^a and 30^b, respectively, contact 29^t and conductor 53 to the negative conductor 45. The armature being connected across the low-voltage conductors with all the armature resistance in circuit and the field being connected across the high-voltage conductors with all the field resistance out of circuit, the motor will operate at its lowest speed. When the contact 25^b, 25^c, 25^d, and 25^e come into engagement with the contact-fingers 26^b, 26^c, 26^d, and 26^e, respectively, the armature resistance will be removed from circuit, and thus the speed of the motor will be increased. The brushes 30^a and 30^b will 85 now come into engagement with contacts 29^b, 29^c, 29^d, 29^e, 29^f, 29^g, 29^h, and 29ⁱ, and thus the field resistance 40, which has previously been short-circuited, will be stepped into circuit to further increase the speed of the motor. At this stage in the operation of the 90 motor the contact 23 leaves the contact-finger 24^a and comes into engagement with the contact-finger 24^b to connect the armature between the high-voltage conductors, and the 95 armature resistance is reinserted in circuit with the armature. The armature-circuit now exists from the positive conductor 43 through the contact-finger 15^b, contacts 13^d and 13^e, contact-finger 15^a, blow-out magnet 100 18, conductor 46, contact-finger 14^d, contact 10^c and 10^d, respectively, contact-finger 14^t, conductor 47, armature 41, conductor 48, contact-finger 14^e, conductor 49, contact-finger 14^b, contacts 10^b and 10^a, respectively, 105 contact-finger 14^a, conductor 50, contact-finger 26^t, all the armature resistance 39, contact-finger 26^t, contact 25^a, contact 23, contact-finger 24^b, and conductor 54 to the negative conductor 45. When the contact 110 23 passes from engagement with the contact-finger 24^a and comes into engagement with the contact-finger 24^b, the contacts 13^a and 13^b leave the contact-fingers 15^a and 15^b, respectively, and contacts 13^c and 13^d come 115 into engagement with said contact-fingers. The main circuit is thus opened at the motor switch-contacts while the change is being made in the armature-circuit. If any arc forms between the motor-switch contacts, it 120 will be extinguished by the blow-out magnet, and consequently any arc which tends to form at other contacts will be disrupted. During the movement of the controller to change the armature-circuits and reinsert the armature resistance in circuit the field resistance 40 will be removed from circuit. The field will remain connected between the high-voltage conductors, and hence the circuit thereof will not be changed. When the 125 130

contacts 25^b to 25^e, inclusive, come into engagement with the fingers 26^g to 26^j, inclusive, respectively, the armature resistance will be again removed from circuit, and after 5 this occurs the brushes 30^a and 30^b will pass over contacts to reinsert the field resistance 40 in circuit with the field.

If the controller-handle be turned in the reverse direction, then the armature-circuit 10 will be closed from the contact-finger 14^d through contact-segments 10^a and 10^b, contact-finger 14^e, conductor 48, armature 41, conductor 47, contact-finger 14^f, conductor 55, contact-finger 14^e, contact-segment 10^d 15 and 10^c, respectively, and contact-finger 14^a to conductor 50, and consequently the motor would run in the opposite direction from that which it did before. All other circuits would remain substantially the same as before. 20

It will be observed that with this controller the speed of the motor may be increased, first, by connecting the armature to a low-voltage source of electrical energy 25 and decreasing the resistance in the armature-circuit; second, increasing the resistance in the field-circuit; third, connecting the armature to a high-voltage source of electrical energy and again decreasing the resistance 30 in the armature-circuit, and, finally, again increasing the resistance in the field-circuit. Consequently the speed of the motor may be widely varied.

It will be understood that various features of the present invention may be applied to different purposes than those which have been herein mentioned and that many changes may be made in the embodiment of the invention herein set forth.

Having described my invention, what I claim as new, and desire to secure by Letters Patent, is—

1. In a motor-controller, in combination a 45 rotatable member carrying contacts and arranged to be rotated in either direction from the initial position thereof to control the direction of operation of the motor, another rotatable member also carrying contacts and arranged to control the resistance of the motor and connect said motor with a high-voltage 50 source of electrical energy, and with a low-voltage source of electrical energy, means operated by the first member, and rotating said second member always in the 55 same direction.

2. In a motor-controller, in combination a rotatable member carrying contacts and arranged to be rotated in either direction from the initial position for controlling the direction of operation of the motor, another rotatable member carrying contacts and arranged to control the resistance of said motor and connect said motor with a source of low-voltage electrical energy, and with a 65 source of high-voltage electrical energy, a

handle for operating the former member, a gear fastened to the latter member and having the gear meshing therewith, an arm attached to the former member, and a link connecting said arm to the latter gear. 70

3. In a motor-controller, in combination a rotatable member carrying contacts and adapted to be rotated in either direction from the initial position thereof, circuit-terminals adapted to be engaged by said contacts for 75 controlling the direction of operation of the motor, another rotatable member also carrying contacts, resistance-terminals adapted to be engaged by said latter contacts, contact-terminals connected with a source of high-voltage electrical energy, and contact-terminals connected with a source of low-voltage electrical energy adapted to be engaged by contacts carried on said second rotatable member, and means operated by the former 85 member and adapted to rotate the latter member always in the same direction from the initial position thereof.

4. In a motor-controller, in combination a rotatable member carrying contacts and 90 adapted to rotate in either direction from the initial position thereof, circuit-terminals adapted to be engaged by said contacts to control the direction of operation of the motor, another rotatable member also carrying 95 contacts, resistance-terminals adapted to be engaged by the latter contacts, terminals connected with a source of high-voltage electrical energy, terminals connected with a source of low-voltage electrical energy also 100 adapted to be engaged by contacts carried by said second-mentioned member, a gear fastened to said latter member and having a gear meshing therewith, an arm fastened to the former member and a link connecting 105 said arm to the latter gear.

5. In a motor-controller, in combination a rotatable member adapted to be rotated in either direction from the initial position thereof, reversible switch-contacts carried 110 by said member, circuit-terminals adapted to be engaged by said contacts whereby the direction of operation of the motor is controlled, another rotatable member also carrying contacts, resistance-terminals adapted to 115 be engaged by the latter contacts, terminals connected with a source of high-voltage electrical energy, terminals connected with a source of low-voltage electrical energy arranged to be engaged by contacts carried by 120 said second-mentioned member, resistance-terminals adapted to be engaged by contacts carried by said second-mentioned rotatable member, and means operated by the former member and adapted to rotate the latter 125 member, always in the same direction from the initial position thereof.

6. In a motor-controller, in combination a rotatable member, adapted to be rotated in either direction from the initial position 130

thereof, reversible switch-contacts carried by said member, circuit-terminals adapted to be engaged by said contacts whereby the direction of operation of the motor is controlled and another rotatable member also carrying contacts, resistance-terminals adapted to be engaged by the latter contacts, terminals connected with a source of high-voltage electrical energy, terminals connected with a source of low-voltage electrical energy arranged to be engaged by contacts carried by said second-mentioned member, a gear fastened to the latter member and having a gear meshing therewith, an arm fastened to the former member, and a link connecting the latter gear to said arm.

7. In combination, a rotatable member adapted to be rotated in either direction from the initial position thereof, reversing switch-contacts carried thereby, circuit-terminals adapted to be engaged by said contacts, another rotatable member, contacts arranged cylindrically upon the latter member, resistance-terminals adapted to be engaged by the latter contacts, resistance-terminals arranged in a plane substantially perpendicular to the axis of the latter rotatable member, contacts carried by the latter rotatable member and adapted to engage the latter resistance-terminals, and means operated by the former member and adapted to rotate the latter member always in the same direction from the initial position thereof.

8. In a motor-controller, in combination a rotatable member carrying contacts, circuit-terminals adapted to be engaged by said contacts whereby the direction of operation of the motor is controlled, another rotatable member also carrying contacts, terminals connected with a source of high-voltage electrical energy, terminals connected with a source of low-voltage electrical energy adapted to be engaged by said latter contacts, resistance-terminals adapted to be engaged by contacts carried by said second-mentioned rotatable member and a blow-out magnet adapted to extinguish any arc which may form at the contacts upon one of said members to prevent an arc forming at the contacts of the other member.

9. In combination, a rotatable member

adapted to be rotated in either direction from the initial position thereof, a handle for turning said member, reversing switch-contacts carried by said member, circuit-terminals 55 adapted to be engaged by said contacts, main switch-contacts also carried by said member, circuit-terminals adapted to be engaged by said main switch-contacts, another rotatable member also carrying contacts, resistance-60 terminals adapted to be engaged thereby, a blow-out magnet for disrupting any arc which may be formed between the main switch-contacts and the terminals engaging therewith, and means operated by the former 65 member and adapted to drive the latter member always in the same direction from the initial position thereof.

10. In a motor-controller, in combination a rotatable member adapted to be rotated in either direction from the initial position thereof, a handle for operating said member, reversing switch-contacts carried by said member, circuit-terminals adapted to be engaged by said contacts whereby the direction 70 of operation of the motor is controlled, another rotatable member carrying contacts, resistance-terminals adapted to be engaged by said contacts, terminals connected with a source of low-voltage electrical energy, terminals connected with a source of high-voltage electrical energy, and adapted to be engaged by contacts carried by said latter-mentioned member, a gear attached to the latter member, and having a gear meshing 80 therewith, the latter gear being pivoted upon a stationary support, an arm attached to the former member and a link connecting said arm to the pivoted gear, the point of connection of said link to said arm being substantially in alignment with the point of connection 85 of said link to said pivoted gear and the axis of said rotatable member when the rotatable members are in the initial position thereof.

In witness whereof I have hereunto subscribed my name in the presence of two witnesses.

THOMAS E. BARNUM.
